UNITED STATES PATENT OFFICE

MARTIN B. CHITTICK, OF CHICAGO, ILLINOIS, ASSIGNOR TO THE PURE OIL COMPANY, OF CHICAGO, ILLINOIS, A CORPORATION OF OHIO

TUBULAR OIL CONVERTER

Application filed June 19, 1930. Serial No. 462,361.

This invention relates to improvements in tubular heaters, and has particular reference to improvements in tubular oil cracking stills wherein vaporized oils are subjected to high temperatures to effect their molecular decomposition.

It is a common practice to pass vaporized oils in an elongated stream of restricted cross-section through the tubular passes, banks or coils of an oil heater wherein the oils are brought to cracking temperatures which are frequently in excess of 1000° F. The oil vapors in passing through the externally heated pipes or tubes of such apparatus contact with the heated walls while traveling at high velocity so that heat exchange takes place, the temperature of the tube walls and the velocity of the vapors having an important bearing on the rate of heat transfer. It has been observed that in high temperature oil cracking heaters wherein oil in the vapor phase is heated to conversion temperatures, for example, between 1000° F. and 1200° F., not only are low boiling point oils of gasoline range produced from higher boiling oils, but in addition there are also produced large quantities of fixed gas and free carbon, the gas being discharged from the heaters with the cracked vaporized products while the carbon tends, at least, in part, to produce a hardened encrustation or coating on the inner walls of the heater tubes which interferes with the heating efficiency of such tubes and, also, results in relatively short life thereof.

This condition is thought to be due to the fact that while the oil vapor is passing through a highly heated tube the annular film or strata of the oil vapor nearest or in contact with the inner wall of the tube is overheated. That is to say, that portion of the oil vapor which contacts directly with the highly heated surfaces of the heater tubes attains a temperature considerably above the desired average or mean cracking temperature, with the result that this portion of the oil vapor is overly heated producing therein violent splitting or decomposition reactions which produce the fixed or permanent gas and carbon deposition. Oil

is a relatively poor conductor for heat and as a result the oil in the center or axial portion of the vapor stream passing through the heater tubes is, in fact, underheated insofar as a desired cracking temperature is concerned. This condition results in a low rate of cracking of the oil vapor for each passage of the latter through the heater, with the result that large quantities of recycle stock are produced which must be again passed through the heater for additional treatment.

To improve this condition it has been proposed heretofore to provide oil converters with tubes of relatively small diameter in order to provide but small volumes of oil vapor in any one of such tubes in comparison with the heating surface present. Small tubes, however, lead to mechanical difficulties, particularly in high temperature apparatus wherein furnace temperatures of the order of 1500 to 2000° F. are employed. It has also been suggested to employ tubes of larger diameter which are capable of withstanding the severe furnace temperatures without rapid deterioration and to provide the interiors of such tubes with longitudinally extending cores which restrict the internal cross-sectional area of the tubes, which provide higher vapor velocities and limit the vapor in any one tube.

While these expediencies have improved to some degree the heating of oil vapor in a more uniform manner to a desired cracking temperature, the fundamental objections above noted with respect to lack of uniformity of heating the entire mass of oil vapor passing through the tubes still obtains, with the result that carbon deposition persists in the converter tubes and fixed gas formation is unduly high.

The present invention provides for the more uniform heating of the oil vapor passing through an externally heated tubular converter (or oil heater) by providing the tubes of such converters with longitudinally extending cores consisting of helical metallic strips which are so shaped and proportioned that as the oil or oil vapor passes longitudinally through the tubes equipped with such

strips or cores, the fluid undergoing heating, in conforming to the shape of the cores, is given a swirling, helical or rotary motion producing sufficient turbulence of flow 5 to bring all portions of such fluid into contact with the heated walls of the tubes, whereby such fluid is uniformly heated to desired temperatures and, specifically, under or over heating of various portions or fractions 10 of the fluid is avoided.

It is another object of the invention to provide the helically bent strips or cores with outwardly projecting lugs or prongs, which engage with the inner walls of the 15 header tubes in which such cores are positioned in order to positively retain the cores in desired operating positions within the tubes and to prevent accidental displacement thereof.

20 It is a further object of the invention to provide the helically bent strips or cores with operating stems which terminate in actuating portions disposed exteriorly of the header and whereby through the provision 25 of such actuating portions the cores may be rotated axially within the tubes in which they are operatively positioned or moved longitudinally of such tubes to obtain desired operating positions on the part thereof 30 while the heater is in operation.

For a further understanding of the invention reference is to be had to the following description and to the accompanying drawing, wherein:

35 Figure 1 is a vertical longitudinal sectional view taken through one of the tubes of an oil converter provided with a helical core formed in accordance with the present invention,

40 Figure 2 is a transverse sectional view taken on the line 2—2 of Figure 1,

Figure 3 is a front elevation of the actuating portion of the core, and

45 Figure 4 is a detail perspective view of the core removed from the header.

Referring more particularly to the drawing, the numeral 1 designates a tube of the type used in connection with oil heaters or converters. These tubes are usually mounted 50 within the masonry wall structure of a furnace (not shown) and ordinarily the tube is formed from ferrous alloys which permit the walls thereof to successfully withstand relatively high furnace temperatures for extended periods of operation without mechanical failure. These tubes are frequently formed from chromium containing ferrous alloys or other oxidation resisting metals or, again, ordinary steel tubes are especially 55 treated to enable them to more successfully resist the deleterious action of high temperature furnace gases. In low temperature oil heaters ordinary mild steel tubes may be used. Oils or oil vapors are passed longitudinally through the tube 1 when the latter 60

is in active operation, but in a specific process to which the present invention is particularly applicable oil in a dry vaporized state is passed longitudinally through said tubes and the furnace temperatures surrounding the latter are sufficiently elevated to permit said oil vapors while flowing at high velocity through said tubes to quickly attain a converting temperature varying between 1000° F. and 1250° F. 70 75

To improve heat transfer between the oil vapor and the heated walls of the tube 1, the latter is provided with an axially disposed longitudinally extending core 2. In the specific form of the invention herein disclosed the core consists of a flat metallic strip bent longitudinally and axially into helical form, comprising a plurality of merged helical surfaces of considerable pitch. In the industry, these cores are referred to as helical, and sometimes spiral, bars or strips. Spurs or prongs 3 are struck from or welded to the cores at spaced longitudinal intervals and are so disposed as to engage with the inner walls of said tubes 80 to maintain the cores in their fixed positions of application within the tubes, specifically avoiding accidental displacement of the cores while the oil heater is in operation. 85 90 95

The tube 1 is connected at one end with a header 4 to which oil vapor is supplied from any suitable source. In alignment with the tube 1 the header has its front wall provided with an opening 5 which is normally closed by means of a key plug 6 100 securely held in place by means of threaded positioning elements 7. The key plug carries a rigidly connected stuffing box 8 which receives a stem 9 projecting axially and forwardly from each core 2. Exteriorly of the header and of the oil heater each stem 9 is provided with an operating handle 10 which may be manually actuated in order to secure circular rotary movement of each core or the longitudinal adjustment thereof within 105 its supporting tube. These adjustments may be obtained without interfering with the active operation of the heater. 110

By the employment of the construction, disclosed the oil vapor passing from the header through the tube 1 contacts with the helical surfaces of the core 2 and is given a rapid swirling turbulent flow while passing longitudinally through the tube. This brings all portions of the oil vapor into contact with the highly heated surfaces of said tube (or tubes) so that such oil vapor is uniformly heated to a desired operating temperature. Thus the evils due to under-heating or overheating of various fractions 120 of the oil vapor are eliminated and high yields of desired compounds obtained. 125

What is claimed is:

1. In apparatus for heating oil in the vapor phase, a tube, a core consisting of a 130

helically twisted metallic bar arranged longitudinally in the tube, and an operating stem connected with one end of said core and having an operating portion arranged 5 exteriorly of the cracking apparatus for adjusting said core rotatably and longitudinally within said tube.

2. In an oil converter, a header, a tube connected with said header and in open communication with the interior thereof, a helical core positioned longitudinally within said tube, and an operating stem connected with one end of said core and terminating exteriorly of said header to provide for rotary and longitudinal adjustment of the core 10 within said tube during the active operation of the converter.

3. In an oil converter, a header, a tube connected with one of the walls of said header and arranged in registration with an opening formed in the opposite wall of the header, a key plug normally closing said latter opening, a helical core arranged in 15 said tube, and an operating stem connected with said core and movably supported by said key plug, said stem terminating in an operating portion arranged exteriorly of the header to provide for the rotary and longitudinal adjustment of the core within said 20 tube.

4. In apparatus for cracking oil in the vapor phase, an externally heated tube, a helically twisted metallic bar positioned longitudinally within said tube and spaced substantially from the inner walls of said tube and a plurality of longitudinally spaced positioning spurs projecting laterally from the edge portions of said bar and contacting with the inner walls of said tube to maintain said bar in an axial position within the tube with the edge portions of said bar spaced from the inner walls of the tube. 25

In testimony whereof I affix my signature.
MARTIN B. CHITTICK.
